(74) Attorney, Agent, or Firm — Quarles & Brady LLP

(57) **CLAIM**

The ornamental design for a dual encoder button, as shown and described.

DESCRIPTION

FIG. 1 is a photograph of a top, side view of a dual encoder button embodying my new design;

FIG. 2 is a photograph of a top view thereof; and,

FIG. 3 is a photograph of a side view thereof.

The bottom view forms no part of the claimed design.
